UNITED STATES PATENT OFFICE.

JACOB F. WEITZEL, OF CINCINNATI, OHIO.

FRUIT-CAN-SOLDERING TOOL.

SPECIFICATION forming part of Letters Patent No. 257,794, dated May 9, 1882.

Application filed April 14, 1882. (Model.)

To all whom it may concern:

Be it known that I, JACOB F. WEITZEL, of Cincinnati, Ohio, have invented a new and useful Tool for Holding Cans to be Soldered, 5 of which the following is a specification.

My invention relates to an improved device for expanding the unsoldered body of a fruit or other can against the upset rims or flanges of the top and bottom plates, and for retaining and holding the same firmly in position during the act of soldering.

My said tool comprises a handled stem or rod united by parallel-rule links to a congeries of curved plates, which, by the simple act of inserting the head of the instrument into the can and then pressing its handle downward, operate to expand the can-body tightly against the marginal rims in proper position for soldering, the handle of the instrument affording a 15 convenient means of grasping the work and of turning it around with one hand while the soldering-bit is applied with the other hand. The said links consist of thin strips of spring metal somewhat bent to secure the necessary elasticity, and the form and arrangement of the parts are such that the tool becomes automatically locked to the expanded condition by the mere act of thrusting it into the unsoldered can.

30 In the accompanying drawings, Figure 1 is a perspective view of my tool in its collapsed condition and about to be inserted in the unsoldered can. Figs. 2 and 3 are respectively an elevation and a transverse section of the same. Fig. 4 is an elevation, and Fig. 5 a transverse section, of the tool expanded within the can. Fig. 6 represents a can clamped upon the expanded holder and in the act of being soldered.

40 A, B, and C may represent respectively the unsoldered bottom, body, and top of an ordinary fruit-can.

My combined clamp and holder is of the following construction: A wooden handle, D, having a metallic ferrule, E, is cross-kerfed, *d*, to receive a shank, F, of the represented X-formed transverse section. The shank F is preferably composed of the represented four L-formed strips of sheet-iron, so as to present four equidistant wings, *f f' f'' f'''*. To each wing is hinged, as at G, two "parallel-rule" links or

toggles, H, making eight in all, or four pairs of such links. Each link is bent flatwise, as shown, to secure the necessary elasticity, and is partly rounded and partly square at each 55 extremity, as shown, so as to limit the folding of the links to the downward direction, (see Fig. 2,) and in the upward direction only so far beyond the horizontal as to secure a lock. (See Fig. 4.) The outer extremities of each 60 pair of links are hinged to the concave face of a plate, J, in the form of a cylindrical arc of diameter corresponding to that of the interior of the finished can-body. There are consequently four of such plates equidistantly disposed around the circuit of the can-body. The parts are so proportioned that the foot of the shank F, when left at liberty, never quite touches the can-bottom, and so that when at its lowest point the hinge attachment to the shank passes 70 a little beyond the straight line intersecting the attachment to the plates, so as to lock the parts to such expanded condition with sufficient stability to insure against accidental displacement. (See Fig. 4.) The unsoldered can having been thus clamped and its body pressed 75 snugly against the end-plate flanges, the operator, grasping the handle D in one hand and the soldering-bit in the other hand, as indicated in Fig. 6, proceeds to solder the joints, 80 which having been effected, a brisk upward movement of the tool liberates it for use upon the next can.

For use with cans of larger size the number of expanders J and of their described coating 85 members may be increased in proportion.

The stem F is preferably constructed as described; but it may be of other forms—such, for example, as a single rod of X-formed transverse section, or of two rods of T-formed transverse section; or the rod may be of square or of cylindrical section and be slotted to receive the inner ends of the links.

I am aware that an entering rod connected by toggle-links to expanding plates has been 95 employed for clamping unsoldered cans for soldering, and I therefore disclaim invention in such expedients, broadly.

I claim as new and of my invention—

1. In a tool for holding cans to be soldered, 100 the handled shank or stem D F, so connected to a congeries of equidistant expanders or arc-

plates J by as many pairs of curved elastic parallel-rule links H as to become self-locking in the act of insertion, substantially as set forth.

5 2. In combination with a congeries of arc-plates, H, arranged equidistantly around the circle, and with as many pairs of curved elastic hinged links H, the X-formed stem F, having the handle D, substantially as set forth.

10 3. In combination with the expanders J and

the curved elastic hinged links H, the stem F, composed of four L-formed strips, and occupying a cruciform kerf, d, in handle D, in the manner described.

In testimony of which invention I hereunto 15 set my hand.

JACOB F. WEITZEL.
